UNITED STATES PATENT OFFICE.

ANGELICA HOFHEIMER, OF BROOKLYN, NEW YORK.

DESIGN FOR A MAIL-BOX.

SPECIFICATION forming part of Design No. 25,536, dated May 19, 1896.

Application filed September 19, 1895. Serial No. 563,039. Term of patent 3½ years.

To all whom it may concern:

Be it known that I, ANGELICA HOFHEIMER, a citizen of the United States, residing in the city of Brooklyn, in the county of Kings and State of New York, have invented and produced a new and original Design for Mailing Boxes or Receptacles, of which the following is a specification, reference being had to the accompanying drawing, forming a part thereof, which represents a perspective view of the front of my design.

The leading feature of my design consists in a rectangular box A, provided with an upwardly-extending back portion B, the extended portion projecting upwardly to a distance about the same as the depth of the box, said box being also provided with a rectangular bottom portion and substantially square end portions C and D and a rectangular front

or side E, the form or configuration of the box 20 being substantially that of a receptacle all angles of which are right angles and one of the sides of which is extended upwardly above the level of the box, and about the center of the box-front is formed a circle H, from which 25 lines G radiate to the corners of said front.

Having fully described my new and original design, what I claim, and desire to secure by Letters Patent, is—

The design for a mail-box, substantially as 30 herein shown and described.

In testimony that I claim the foregoing as my invention I have signed my name in the presence of two witnesses.

ANGELICA HOFHEIMER.

Witnesses:

C. GERST,

A. M. CUSACK.
